CLAIM

The ornamental design for a dental device, as shown and described.

DESCRIPTION

FIG. 1 is a front view of a dental device, namely a dental printer.

FIG. 2 is a left side view thereof.

FIG. 3 is a right side view thereof.

FIG. 4 is a top view thereof.

FIG. 5 is a rear view thereof.

FIG. 6 is a bottom plan view thereof; and,

FIG. 7 is a perspective view thereof.

The broken lines in the drawings depict portions of the dental device and form no part of the claimed design.
